TEXTILE-STORAGE APPARATUS.

1,123,138.

Specification of Letters Patent. Patented Dec. 29, 1914.

Original application filed June 9, 1913, Serial No. 772,596. Divided and this application filed March 31, 1914. Serial No. 833,639.

To all whom it may concern:

Be it known that I, ISAAC E. PALMER, a citizen of the United States, and a resident of Middletown, county of Middlesex, State 5 of Connecticut, have invented an Improvement in Textile-Storage Apparatus, of which the following description, in connection with the accompanying drawings, is a specification, like characters on the drawings 10 representing like parts.

This invention relates to textile storage apparatus and preferably to apparatus adapted for the continuous storage of textile material.

15 This application is a division of my pending application Serial No. 772,596 filed June 9, 1913.

In order that the principle of the invention may be readily understood, I have disclosed a single embodiment thereof in the accompanying drawings, wherein—

Figure 1 is a view partially in vertical section and partially in end elevation of one form of apparatus embodying my invention; 25 Fig. 1^a is a detail in plan of a slightly modified construction. Fig. 2^a is a side elevation. Fig. 2 is a front elevation, partially in transverse section, of the apparatus shown in Fig. 1; Fig. 3 is a side elevation of the 30 lower part of the construction shown in Figs. 1 and 2; Fig. 4 is a side elevation of the lower portion of the apparatus and representing a modified form thereof wherein positively driven rolls are employed near 35 the discharge end thereof; Fig. 5 is a detail in section representing said positively driven rolls and the related parts; Fig. 6 is a detail in longitudinal vertical section of the preferred form of roller employed at the discharge end of the apparatus; and Fig. 7 is 40 a detail in plan showing said rolls.

This invention relates to textile storage apparatus and is an improvement upon the construction shown in my Patents No. 408,388, August 6, 1899; No. 653,485, July 45 10, 1900; No. 971,778, October 4, 1910; and No. 1,033,925, July 30, 1912.

As shown in my patents above referred to, textile material in lengths, such, for example, as yarn or cloth in rope-like form or even in widths, has been piled or folded into the open upper ends of J or U-shaped chutes,

the material being treated either prior to or during its passage through said chute to the action of some suitable liquor, such for example, as a bleaching, dyeing, finishing or other conditioning liquor. As disclosed in my said Patent No. 408,388, the front and rear walls of said chute are made of power driven aprons to facilitate the passage of material therethrough. As shown in my Patent No. 653,485, I have facilitated the passage of the material through the chute by maintaining a flow of liquor sufficient to float the material therethrough. In my Patent No. 971,778, I have represented a chute of J form grooved for the downward flow of a treating liquor and having material traversing and feeding mechanism for feeding the material into the upper end of the chute. 70 In my Patent No. 1,033,925, I have disclosed a chute of the J type and in certain forms thereof have represented the rear and bottom walls as having a series of freely rotating rolls to decrease the frictional resistance to the onward movement of the material. In the present application I disclose but do not claim *per se*, means for feeding the material into the upper end of the chute or other suitable receiver, and disclose and 75 claim an improved form of chute, preferably of the J type, a particular object of the improved form of chute being to control the discharge of the material therefrom and to insure its discharge in a regular and even 80 manner and without undue choking or tangling.

The material is delivered into the open, upper end of the preferably substantially upright chute and is gradually delivered 90 therethrough by suitable feeding mechanism preferably adapted to deposit the material in folds in the upper end of the chute, one type of mechanism for accomplishing this purpose being disclosed herein.

In accordance with the preferred use of my invention, the textile material may be discharged or drawn either in a saturated or wet condition or in a squeezed condition from the chute or receiver. That is to say, 95 the apparatus is adapted to receive material which may be in rope or chain form, or as yarn, or in the condition of flat goods of suitable width, such material being prefer-

ably treated, either in the apparatus or previous to its entrance thereto, with any suitable conditioning liquor, such, of example, as a bleaching, dyeing, finishing or other liquor, or just prior to the delivery of the material into the chute, the conditioning liquor, of whatever nature, may be substantially expelled therefrom by the action of the squeeze rolls, so that while the material 5 remains in the chute, the comparatively small amount of treating liquor yet remaining in the goods may continue to act thereon, and, if desired, until the force of such treating liquor is exhausted. For example, 10 the material prior to its delivery into the chute may be subjected to the action of a bleaching liquor, and the greater proportion of this bleaching liquor may be expelled therefrom by squeeze rolls prior to the delivery of the material into the chute. This permits the continued action upon the material of a weak bleaching liquor, so that the time may be prolonged without injury to the material, such as would result if a bleaching 15 liquor of full strength were permitted to act upon the material for any considerable period.

Referring more particularly to the drawings, and first to that form of my invention 20 shown in Figs. 1 to 3 inclusive and Fig. 6, I have therein represented a chute of substantially J form and having a front wall 1, a rear wall 2, and side walls 3 and 4. The said chute is supported in any suitable manner, as for example, by or between suitable 25 beams or uprights 5 connected at their upper ends by suitable cross beams 6. If desired, the said chute may be mounted within a suitable tank into or through which the 30 material may be discharged from the chute. Also, I may provide suitable means, such, for example, as indicated in my Patent No. 971,778, for introducing a treating or other liquor into the upper portion of the chute. 35 Such liquor may be employed for the purpose of treating the material, and may be of any suitable nature, as, for example, bleaching, dyeing, or finishing liquor, or it may be water or other liquid employed 40 merely to facilitate the passage of the material through the chute.

The walls of the chute may be of any suitable material. I have represented the front wall 1 as composed of upright, wooden 45 strips 7 and the rear wall as composed of wooden strips 8 transversely arranged. Preferably the front wall 1 of the chute is vertical, and preferably the rear wall 2 is also vertical, though within the scope of my 50 invention either one or both of the walls may be inclined so as gradually to increase the cross sectional area of the chute in the direction of the passage of the material therethrough. Preferably, however, I provide for an increasing cross sectional area 55

in the direction of the passage of the material through the chute by forming the side walls 3, 4 with stepped portions, as indicated at 9, 9' in Fig. 2, it being understood that such stepped portions may be provided 60 at any desired number of points between the top and the bottom of said side walls.

The lower portion 10 of the rear wall 2 is suitably curved or inclined, as indicated in Fig. 1, the prolongation of said curved portion constituting the bottom of the chute and whereon the material is wholly supported just prior to its discharge from the chute. The provision of this curved or inclined portion of the chute makes the rear 70 and bottom wall of the chute of greater length than the front wall thereof, assuming the same to be continued to a corresponding point, and this greater length is preferably substantially compensated for by the 75 provision of some suitable lining, such, for example, as the lining 11 of sheet copper extending preferably throughout the curved portion of the rear wall of the chute.

If desired, I may provide any suitable 80 means for circulating liquor through the chute; that is to say, the chute may be supported in a suitable tank, and the liquor discharged into the upper end of the chute, so as to pass down therethrough into the tank, and then to be withdrawn from the tank and re-introduced into the upper end of the chute, substantially as indicated in my Patent No. 971,778.

While the apparatus is mainly intended 90 for treating the material in rope form, as, for example, narrow goods or yarn, it is also adapted for treating goods in lengths in a flat condition, and in order to accommodate different widths of goods, the side walls 95 may be adjustable toward and from each other in any suitable manner. The front wall 1 may be adjusted in and out with respect to the rear wall 2, so as to facilitate the laying of the material in folds of the desired extent. I have herein represented the front wall as supported between the side walls 3, 4, and as provided adjacent its upper and lower ends with pairs of brackets 100 12, 13, having rack teeth 14 upon their under edges with which mesh pinions 15 upon rods 16 supported in suitable brackets 17 upon said sides. One of said rods 16 is provided with a hand wheel 18, and sprocket chains 19 are provided to compel uniform 105 adjustment of the front wall 1 in and out upon rotation of said hand wheel 18.

At some suitable part of the front wall 1, and, as here shown, substantially in the horizontal plane of the upper end of the curved portion 10 of the rear wall, I provide a movable member, here shown as a former or apron 20 hinged at 21 to the lower edge of the vertical portion of the front wall, but so 110 that its inner face is flush with the inner 115 120 125 130

face of the front wall. The said former or apron 20 is preferably formed in two parts, the lower part being adapted to be extended inwardly toward the curved rear wall 10 at 5 suitable times, as, for example, upon the commencement of the piling down operation, thus constituting a temporary support for the material. For this purpose, I have represented the apron or former 20 as having 10 hinged thereto at 22 a material supporting member 23 preferably of sufficient area substantially to fill or block the lower end of the chute when in an infolded position, as indicated in Fig. 1. I have provided self- 15 acting means adapted to hold the said supporting member 23 in the position shown in Fig. 1 but permitting it to be positioned at substantially right angles thereto, in which latter case it acts as a prolongation of the 20 main portion of the apron 20. For this purpose, I have herein provided a relatively heavy weight 24 secured by a bracket 25 and bolt 26 to the outer face of the supporting member 23. When the weight is in the 25 position shown in Fig. 1, it holds the supporting member 23 across the mouth of the chute, and the weight may be sufficient thus to support the material until the weight is swung against the outer wall of the upper 30 portion of the former 20 when the lower portion of the former will be in general parallelism in its new position with the curved rear wall 11, and press with the desired force against the material, or the weight 24 may 35 be merely sufficient to support the material until a substantial amount thereof has accumulated in the chute, whereupon a further accumulation of the material causes the former to swing into a position at right 40 angles to that shown in Fig. 1.

The side walls, 3, 4 of the chute are preferably of greater width at the lower end of the chute, as indicated in Fig. 1 and each 45 preferably terminates in a vertical or up-right edge 27, which is here represented as extending downward to a point 28 close to the termination of the curved portion 10 of the rear wall 2. The said side walls 3, 4 thus reduced in height, are continued forward, as indicated at 29, and are upwardly curved, as at 30, in general parallelism with the forward, upwardly turned extension 31 of the curved, rear wall 10. Viewing Fig. 1, 50 it will be noted that the forward edge of the curved wall 10 terminates more or less abruptly adjacent to or in the plane of the upright edges 27 of the side walls, and that the continuation 31 of the curved portion of the rear wall lies at its rear in a lower plane 55 than the said curved portion 10. In advance of the curved portion 10 and leading directly forward therefrom, I provide a series of relatively narrow strips 32, here represented as four in number, and which 60 are tapered at their forward portions, so as

to afford an exit for the material along their upper edges. The said strips 32 not only serve to support the material at spaced points, but they also form between them pockets or depressions and prevent the sudden pulling out of a long piece or portion of the material, as might occur if the material becomes choked for any reason, and then suddenly yields to the pull of the mechanism to which the material is fed from the chute. 70 In other words, the strips localize the discharge of the material and restrict the length thereof that can be pulled out at any given time, even under undue tension or strain. 80

The provision of a depression at the leading edge of the curved portion 10 adjacent to the supporting board 33 is an important feature of my invention. As hereinafter set forth, it is evident that the supporting board 85 33 may be positioned at any suitable angle and that, if desired, it may be inclined with its inner face directed inwardly and downwardly. The material descending through the chute or receiver accumulates in folds or 90 layers which contact with the inner face of the supporting board 33, whether the latter be vertical or inclined, and also with the inner face of the curved portion 10, thus extending across the discharge throat. As the 95 material is drawn out through the discharge throat the depression at the leading edge of the curved portion 10 permits that portion of the column which is contacting with the inner face of the supporting board 33 to 100 gradually move downward toward the exit throat thus preventing any clogging or binding of the material. In other words, the depression at the leading edge of the curved portion 10 effects an easing up of the material bearing against the inner face of the 105 supporting board 33 so that the material is drawn through the exit throat both from the inner face of the supporting board 33 and from the upper face of the curved portion 10 with equal tension and without undue strain. 110

At a suitable point in advance of the up-right edges 27 of the sides 3, 4, I provide a supporting board 33, here shown as upright, 115 and having a series of spaced strips 34 secured or formed upon its inner face and against which the material accumulates in its passage through the lower end of the chute. These strips are shown as tapered 120 downwardly and preferably the lower end of the supporting board 33 is lined with sheet copper or other like substance to facilitate the passage of the material through the chute. 125

I have herein represented the supporting board 33 as mounted or carried by the side walls 3 and 4, and preferably adjusted with respect thereto. Herein for the purpose, I have represented said board as provided 130

with T-shaped brackets, the horizontal members 37 of which are slotted as indicated at 38 for the reception of bolts 39, by which the said supporting board may be secured in 5 any position in and out or up and down with respect to the forward terminals of the rear, curved wall 10 and the strips 32. It will be apparent that the said supporting board 33 may be swung upon the bolts 39 as pivots, 10 or moved in and out in a right line.

In coöperation with the supporting board 33, I preferably provide means to facilitate the discharge of the material through the mouth of the chute. Herein for the purpose, 15 I have represented a roller 40 which may be continuous and may if desired be driven, but which preferably is sectional as indicated in Fig. 6, so that only that portion thereof with which the band or rope of yarn 20 or material is in contact need be rotating at any given time. In this manner, I very markedly reduce the strain upon the material when in rope-like form which would necessarily result from the turning of the 25 entire roller by the stress of the material. While the sectional roller may be of any suitable character, I preferably mount the same loosely upon a fixed shaft or rod 41. Each member 42 of the roller 40, excepting 30 one of the end members, is provided with a metallic or other suitable sleeve 43 fitted tightly onto a portion of the roller of reduced diameter, as indicated at 44, and which encircles a correspondingly reduced 35 portion 45 of the adjacent section of the roller. In other words, the roller sections are nested one onto another and the entire periphery of the composite roller is unbroken. The roller sections 42 are adapted 40 to rotate freely about the shaft or rod 41, but are held against longitudinal movement thereon in any suitable manner, as for example, by the end supports for the roller. Each roller section is preferably formed of 45 wood and the ring-like members 43 are of metal or any suitable material that will not corrode or impair the fabric.

The shaft or rod 41 is preferably mounted in short uprights 46 positioned in advance 50 of the supporting board 33, and above the said roll 40 there may be supported a dash or drain or guide board 47. If desired, the roller 40 and also the board 47 may be supported by the board 33 on suitable extensions therefrom, so that all the said members 55 may be adjusted together along the slotted brackets 36, 37. Such construction is shown in Figs. 1^a and 2^a, wherein the slotted brackets 36, 37 extend to and support the board 60 33, the roller 40 and the board 47.

The material discharged from the chute 65 may be passed to any subsequently acting mechanism or may be re-passed through the chute, and if desired I may provide the latter with a suitable guiding device to shake

out the wrinkles from the material after its passage through the chute. For that purpose, I have in Figs. 1, 2 and 3, represented the uprights 5 as provided with cross pieces 48 projecting beyond the front wall of the 70 chute and having mounted thereon one or more transverse strips 49 slotted as indicated at 50, through which the material may be reversely passed for the purpose stated.

In order to introduce the material into the chute or other receiver, I preferably provide suitable means (of which one type is herein disclosed) to traverse the material when in rope or yarn-like form, and then to 75 fold it back and forth in the upper end of the chute, or merely to fold the material if the latter be wide goods, such means not being herein claimed *per se*. Assuming that the material is in rope or yarn form and that the type of feeding mechanism herein disclosed be employed, it is introduced from the apparatus by which it was last previously treated, or it is reintroduced from the discharge end of the chute, through a suitable pot-eye 51 represented in Figs. 1 and 2. 80

In order to traverse the material from side to side of the chute, I provide any suitable mechanism, such for example, as a sprocket chain 52 represented in Fig. 2 as mounted upon suitable pinions 53, 54, the latter being driven by suitable sprocket gearing 55 from the main drive shaft. The pot-eye is traversed to and fro by the chain 52 and is guided in its to and fro movement by upper and lower guides 56 in a manner 90 not necessary more fully to describe. If desired, it may be traversed in any other manner, as for example, in the manner shown in my Patent No. 971,778.

In order to introduce the material into the 105 upper end of the chute or other receiver, I have herein represented a main drive-shaft 57 having thereon fast and loose pulleys 58, 59 whereby it may be driven from any suitable source. Upon the said shaft 57 is fast a 110 suitable drum 60, about which the material passes, it being directed thereto from the pot-eye 51. The main shaft 57 is supported in suitable bearings in uprights or castings 61 themselves supported upon the upper 115 ends of the uprights 5. The material after passing about the upper surface of the drum 60 thence passes between the drum and the squeeze roll or rider roll 62, which is supported at the lower ends of links 63 pivoted as indicated at 64 in the upper end of the brackets or uprights 61. The squeeze roll 62 rests by gravity against the material and may expel a considerable portion of the liquor therefrom, if the material be received from an apparatus wherein it has been subjected to liquid treatment. 120

Below and between the drum 60 and roll 62, I mount a chute, to which to and fro movement is imparted to fold the material 130

in the upper end of the receiving or storage chute, and which is therein represented as composed of two spaced boards or plates 65, 66, each of which is provided at its ends with metallic hangers 67, the upper ends of which encircle the supports of two clearing rolls or shafts 68, 69, whereby the said boards or plates are supported. It will be observed that the said plates or boards 65, 66 are independently supported as contradistinguished from the construction shown in my Patent No. 971,778.

The boards or plates 65, 66 are connected adjacent their lower ends by bars or strips 15 70, and in order to impart to and fro or swinging movement to said boards or plates, I have herein provided the following mechanism. Upon the main drive shaft 57 is provided a pinion meshing with a pinion 72 20 upon a suitable shaft, the latter also having thereon a sprocket pinion 74. These shafts or rollers 68, 69 are provided with suitable pinions (not shown), and mounted on a shaft 77 in a suitable hanger 78 is a sprocket 25 gear 79, while upon the opposite ends of said shaft 77 is a crank arm 80 connected by link 81 to the plate or board 66. A sprocket chain 82 passes about the said sprocket pinions and sprocket gear 79, the said sprocket 30 chain being driven in such direction as to swing the board 65, 66 to and fro and also to rotate the rollers or shafts 68, 69, preferably at a relatively low rate of speed compared with the peripheral speed of the drum 35 60. The function of the shafts or rollers 68, 69 is to clear the drum 60 and roller 62 from any material that might adhere thereto, and for the purpose each is driven in an opposite direction with respect to the drum 60 and

40 roller 62, and with which they are in contact or substantially in contact. The to and fro movement imparted by the crank 80 and link 81 is sufficient to lay the material in folds in the upper end of the chute, the 45 length of each fold being substantially the depth of the chute from front to rear. By varying the length of the crank arm 80, the length of the folds may be likewise varied.

If desired, I may provide the inner face 50 of the chute or receiver with one or more positively driven rolls. If provided, these rolls are preferably positioned at the inner face of the curved portion 10 of the rear wall 2 and in Figs. 4 and 5 I have represented two such rolls 83 and 84 which are positioned at the extreme lower end of the said curved portion 10. These rolls may be of any suitable character and form but preferably each of said rollers is provided with 55 annular enlargements or shoulder portions 85 which are suitably spaced to provide therebetween recessed portions 86. The annular enlargements 85 of each roller are opposite the recessed portions 86 of the other roller and the described construction pro-

vides an increased or enlarged surface to contact with and effect the forward movement of the material. It will be observed, viewing Fig. 5, that immediately in advance of the rollers 83, 84, I provide a material 70 guiding surface 87, the inner edge of which is at a lower level than the leading edge of the curved surface 10, thus providing a depression 88 for the purpose fully described with reference to the construction shown in 75 Fig. 1.

The positively driven roll or rolls of any suitable type may be omitted, but if employed, any suitable number thereof may be used as for example, one, two, three or 80 more. If employed, they are driven in any suitable manner and when a series thereof is employed, they are rotated in the same direction. I have in Fig. 4 represented suitable driving means consisting of a vertical 85 shaft 89 having any suitable means for driving the same, and preferably gear and sprocket chain connections to the shaft 57. The said rolls may be driven in this manner at any suitable speed. At its lower end the 90 shaft 89, which is mounted in suitable hangers 90, is provided with a worm 91 meshing with a worm wheel 92 upon the shaft of the roller 83. The rollers 83, 84 are both provided with sprocket pinions about which is 95 passed a sprocket chain 93 whereby said rollers are both driven in a forward direction as indicated by arrows in Figs. 4 and 5. Obviously any other suitable driving mechanism may be employed but if the rollers 100 be used they are preferably driven at a slow rate of speed corresponding substantially to that of the desired rate of travel of the material through the chute or receiver.

The apparatus herein shown is adapted to 105 treat material either in rope or flat form, whether woven or in the form of warp. The material may be passed repeatedly through the chute or other receiver, if desired, and may be treated by passing it in succession 110 through a series of chutes wherein different liquors are circulated or provided. It will be evident that the chute of the apparatus is composed wholly or substantially wholly of fixed parts, and that the friction of the material as it is conveyed therethrough is reduced substantially to a minimum. It is also evident that instead of treating the material in the chute with liquor as described, the chute may be used as a time receiver or 115 storage receptacle, from which the material may be drawn in any suitable manner.

By reason of the hereinbefore described relation of the supporting board 33 and the lower end of the curved wall 10, the lower 120 end of the column of folded material is supported with the bends or folds resting against said parts, and the material may be drawn with equal facility from either of 125 said parts without undue choking of the 130

outlet, the area of which may be varied by the adjusting means described. It is, however, important that the material be sufficiently choked at or adjacent the delivery mouth to prevent the same from too free discharge or from flowing off into the tank if treating liquor be provided. I thus restrict the material to a gradual and substantially regular discharge.

Having thus described one illustrative embodiment of my invention, I desire it to be understood that although specific terms are employed, they are used in a generic and descriptive sense and not for purposes of limitation, the scope of the invention being set forth in the following claims.

Claims—

1. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, a fixed wall positioned to restrict the discharge of the material from said delivery mouth, and means to vary the restricted passage provided by said wall.

2. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, and an upright supporting member coöoperating with the bottom wall of the chute to restrict the discharge of the material.

3. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, an upright supporting member coöoperating with the bottom wall of the chute to restrict the discharge of the material, and means to adjust said supporting member.

4. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, an upright supporting member to restrict the discharge of the ma-

terial, and means to adjust said supporting member in a plurality of directions.

5. Textile storage apparatus comprising a chute having an upturned material in-take end and a lower, discharge end having a delivery mouth, and a sectional roller mounted at said mouth and in contact with which the discharging material passes.

6. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, and a sectional roller mounted at the delivery mouth of the chute and in contact therewith the discharging material passes.

7. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, and a plurality of spaced, terminal strips 32 constituting prolongations of said bottom wall of the chute.

8. Textile storage apparatus comprising a chute having an upturned, material in-take end and a lower, discharge end angularly directed with respect thereto and having a delivery mouth, the rear and bottom wall of the chute between said in-take end and delivery mouth being of greater length than the front and upper wall thereof between said points, a plurality of spaced, terminal strips 32 constituting prolongations of said rear wall, and an upright supporting board 33 above and spaced from said strips 32.

9. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, a substantially upright supporting board between which and the bottom wall of the chute the material is discharged, and upright strips or ribs upon the inner face of said board.

10. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof

between said points, and an upright supporting board adjacent to but spaced from the bottom wall of the chute and in advance of the front wall thereof.

5 11. Textile storage apparatus comprising a chute having an upturned, material in-take end and a lower, discharge end angularly directed with respect thereto and having a delivery mouth, the rear and bottom 10 wall of the chute between said in-take end and the delivery mouth being of greater length than the front and upper wall thereof between said points, an upright supporting board adjacent to but spaced from the bottom wall of the chute and in advance of the front wall, and means to adjust said board to vary the area of the outlet.

12. Textile storage apparatus comprising a chute having an upturned, material in-take end and a lower, discharge end angularly directed with respect thereto and having a delivery mouth, the rear and bottom wall of the chute between said in-take end and the delivery mouth being of greater 20 length than the front and upper wall thereof between said points, a friction reducing roller mounted at the delivery mouth of the chute, and means for effecting adjustment of said roller to vary the area of the delivery 25 mouth.

13. Textile storage apparatus comprising a chute having an upturned, material in-take end and a lower, discharge end angularly directed with respect thereto and having a delivery mouth, the rear and bottom wall of the chute between said in-take end and the delivery mouth being of greater length than the front and upper wall thereof between said points, said rear and bottom 30 wall having a friction reducing lining, the chute having a recessed portion adjacent the delivery mouth to prevent undue clogging of the material thereof.

14. Textile storage apparatus comprising a chute having an upturned, material in-take end and a lower, discharge end angularly directed with respect thereto and having a delivery mouth, the rear and bottom wall of the chute between said in-take 45 end and the delivery mouth being of greater length than the front and upper wall thereof between said points, said rear and bottom wall having a friction-reducing lining, and spaced terminal strips 32 constituting 50 prolongations of said lined portion of the rear and bottom wall.

15. Textile storage apparatus comprising a chute having an upturned, material in-take end and a lower, discharge end angularly directed with respect thereto and having a delivery mouth, the rear and bottom wall of the chute between said in-take end and the delivery mouth being of greater 60 length than the front and upper wall there-

of between said points, and an upright supporting board at said delivery mouth, the lower end of the bottom wall and said upright board being arranged at substantially right angles to each other, thereby to constitute supports for the folds of the material. 65 70

16. Textile storage apparatus comprising a chute having an upturned, material in-take end and a lower, discharge end angularly directed with respect thereto and having a delivery mouth, the rear and bottom 75 wall of the chute between said in-take end and the delivery mouth being of greater length than the front and upper wall thereof between said points, an upright supporting board at said delivery mouth, the lower end of the bottom wall and said upright board being arranged at substantially right angles to each other, thereby to constitute supports for the folds of the material, and spaced strips constituting substantial 80 prolongations of said rear and bottom wall.

17. Textile storage apparatus comprising a chute having an up-turned material in-take end and a lower discharge end having a delivery mouth, the front wall of the 90 chute having a former constituting a prolongation of said front wall and mounted to press inwardly against the column of material in the chute, the said former being provided with an extension movable with 95 respect to the main portion of the former into a position across the chute.

18. Textile storage apparatus comprising a chute having an upturned material in-take end and a lower discharge end having a delivery mouth, the front wall of the chute having a former or apron hinged thereto, and adapted to press inwardly against the column of material in the chute, the said former having a secondary member movable 105 with respect to the main portion of the former or apron into a position across the chute.

19. Textile storage apparatus comprising a chute having an upturned material in-take 110 end and a lower discharge end having a delivery mouth, the front wall of the chute having a former or apron hinged thereto, and adapted to press inwardly against the column of material in the chute, the said former having a secondary member movable 115 with respect to the main portion of the former or apron into a position across the chute, and a weight to hold the secondary member in said inward position. 120

20. Textile storage apparatus comprising a chute having an upturned material in-take end and a lower discharge end having a delivery mouth, the front wall of the chute having a hinged former 20 mounted to press 125 inwardly against the column of material in the chute and provided with a secondary member 23 movable with respect to the main

body of the former 20, and means to hold the latter across the chute or to constitute a prolongation of the former 20.

21. Textile storage apparatus comprising a chute having an upturned material intake end and a lower discharge end angularly directed with respect thereto and having a delivery mouth, the rear and bottom wall of said chute between said intake end and the delivery mouth being of greater length than the front and upper wall thereof between said points and a two-part former mounted at the lower end of the front wall of the chute, the upper part of said former constituting a material-guiding member and adapted to press inwardly against the column of material in the chute and the lower part thereof being movable with respect to the upper part and constituting interchangeably a material-supporting or a material-guiding member.

22. Textile storage apparatus comprising a chute having an upturned material intake end and a lower discharge end angularly directed with respect thereto and having a delivery mouth, the rear and bottom wall of the chute adjacent said delivery mouth being downwardly and forwardly inclined, and means to restrict the discharge of the material at and along a portion of the bottom wall of the chute that is inclined downward in a forward direction.

23. Textile storage apparatus comprising a chute having an upturned material intake end and a lower discharge end angularly directed with respect thereto and having a delivery mouth, the rear and bottom wall of the chute adjacent said delivery mouth being downwardly and forwardly inclined, and fixed upright means to restrict the discharge of the material at and along a portion of the forwardly and downwardly inclined bottom wall.

24. Textile storage apparatus comprising a chute having an upturned material intake end and a lower discharge end angularly directed with respect thereto and having a delivery mouth, the rear and bottom wall of the chute adjacent said delivery mouth being downwardly and forwardly inclined, fixed upright means to restrict the discharge of the material at and along a portion of the forwardly and downwardly inclined bottom wall, and means to vary the area of the discharge opening.

25. Textile storage apparatus comprising a chute having an upturned material intake end and a lower discharge end angularly directed with respect thereto and having a delivery mouth, the rear and bottom wall of the chute being inclined forwardly and downwardly, and a fixed wall to restrict the discharge of the material through said delivery mouth.

26. Textile storage apparatus comprising

a chute having an upturned material in-take end and a lower discharge end angularly directed with respect thereto and having a delivery mouth, and means to restrict the discharge of the material from said delivery mouth, the chute having a recessed portion adjacent the delivery mouth to prevent undue clogging of the material thereof.

27. Textile storage apparatus comprising a chute having an upturned material in-take end and a lower discharge end angularly directed with respect thereto and having a delivery mouth, the chute having a rear and bottom forwardly directed wall having a material easing depression adjacent the delivery mouth, and means to restrict the discharge of material from the delivery mouth.

28. Textile storage apparatus comprising a chute having an upturned material in-take end and a lower discharge end angularly directed with respect thereto and having a delivery mouth, said chute having a curved bottom wall 10 and a bottom wall 31 in advance thereof and at a lower level than said wall 10, and coöperating means adjacent the leading edge of the wall 10 to restrict the passage of the material through the chute.

29. Textile storage apparatus comprising a chute having an upturned material in-take end and a lower discharge end angularly directed with respect thereto and having a delivery mouth, a roller positioned within the chute adjacent the delivery mouth and constituting a portion of a wall thereof and means positively to drive said roller.

30. Textile storage apparatus comprising a chute having an upturned material in-take end and a lower discharge end angularly directed with respect thereto and having a delivery mouth, said chute having a curved rear and bottom wall 10, a roller located at the leading edge of said wall 10 and constituting a continuation of said wall, and means positively to rotate said roller.

31. Textile storage apparatus comprising a chute having an upturned material in-take end and a lower discharge end angularly directed with respect thereto and having a delivery mouth, said chute having a curved rear and bottom wall, a plurality of rollers constituting a portion of said bottom wall, and means positively to rotate said rollers in a forward direction.

32. Textile storage apparatus comprising a chute having an upturned material in-take end and a lower discharge end angularly directed with respect thereto and having a delivery mouth, said chute having a curved rear and bottom wall, a plurality of rollers constituting a portion of said bottom wall, and a sprocket chain passing about said rollers to rotate them in the same direction.

33. Textile storage apparatus comprising a chute having an upturned material in-take end and a lower discharge end angularly di-

rected with respect thereto and having a delivery mouth, said chute having a curved rear and bottom wall, a plurality of rollers constituting a portion of said bottom wall, 5 a sprocket chain passing about said rollers to rotate them in the same direction, and means positively to drive said sprocket chain.

Copies of this patent may be obtained for five cents each, by addressing the "Commissioner of Patents, Washington, D. C."

In testimony whereof, I have signed my name to this specification, in the presence of 10 two subscribing witnesses.

ISAAC E. PALMER.
